SAMPLING DEVICE

Joseph L. Shular, East Stone Gap, Va.

Application April 11, 1938, Serial No. 201,401

4 Claims. (Cl. 73—21)

This invention relates to devices known as samplers or riffles, designed for automatically taking samples of free flowing materials such as coal or the like.

5 An important object of the invention is to provide a device of this character which will thoroughly riffle and separate a comparatively small quantity of the material from the flowing mass, to the end that a true sample of the material will be assured.

Another object of the invention is to provide a riffler which is automatic in its operation, and one which may be readily operated to obtain a sample of the material at any time direct from 15 the bins in which the material is held or stored.

Still another object of the invention is to provide a device of this character which may be readily and easily adjusted for use in obtaining samples of various grades of material.

20 With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the invention.

Referring to the drawings:

30 Figure 1 is a side elevational view of a riffler constructed in accordance with the invention.

Figure 2 is a plan view of one section of the riffler, the hinged cover thereof having been broken away to illustrate the interior construction of the riffler.

35 Figure 3 is a section view taken on line 3—3 of Figure 2.

Figure 4 is a sectional view taken on line 4—4 of Figure 2.

40 Figure 5 is an elevational view illustrating the grinding means and substantially small riffler, forming a part thereof.

Figure 6 is a perspective view illustrating a portion of the riffler table, and illustrating the 45 partitions or riffler plates, supported thereon.

Figure 7 is a sectional view taken on line 7—7 of Figure 2.

Figure 8 is a fragmental sectional view illustrating the opening in the bottom of the conveyor 50 housing.

Figure 9 is a sectional detail view illustrating the adjusting means whereby the riffler table is adjusted vertically.

55 Referring to the drawings in detail, the riffler comprises a body portion indicated generally by

the reference character 5, the general contour of the body portion being similar to the construction of the usual hopper bottom bin.

The upper surface of the body portion 5 is inclined, and is normally closed by means of the 5 hinged closure 6. Arranged in spaced relation with the closure 6, is the riffler table 7, which is formed with a plurality of rows of spaced openings 8 which are wide at their upper edges, and narrow off towards the lower ends thereof.

10 Partitions indicated by the reference character 9 extend along the upper surface of the table 7, and divide the surface of the table into a plurality of equal spaces, transversely of the table 7. As clearly shown by Figure 2 of the 15 drawings, these partitions 9 extend over the openings 8 dividing the openings, so that material directed to the table at opposite sides of the partitions 9, may pass through the openings 8. The partitions 9 are arranged in such a way 20 that the openings on opposite sides thereof are disposed in staggered relation with respect to each other. The riffler plates are indicated by the reference character 10 and extend upwardly from the riffler table 7, a distance equal with 25 the height of the partitions 9, the plates 10 extending along the edges of the spaced openings 8, and secured to the riffler table 7, as by welding, throughout portions of the lengths of the riffler plates 10. Offset portions indicated at 11 are 30 formed in the plates 10, and provide baffle surfaces, against which the flowing material strikes, retarding the movement of the flowing material. These offset portions 11 also act to direct the material laterally into the passageways between 35 the riffler plates. It might be stated that these riffler plates 10 merely rest on the table 7, from points adjacent to the offset portions 11 thereof, to the free ends of the plates, thereby providing 40 adjustable end portions which may be readily bent laterally to vary the flare of the free ends of the riffler plates, adapting the device for use in sampling various types of material. Certain of the plates 10 extend into the body portion 5, providing 45 baffles.

45 Due to this construction, it will be seen that because these riffler plates 10 are inclined towards the partitions 9, the free end of one riffler plate lies in spaced relation with the adjacent end of the riffler plate associated therewith, providing 50 passageways between riffler plates, to direct material into the openings 8.

The reference character 12 designates the hopper of the riffler, the hopper being provided with openings 13 and partitions 14 arranged ad- 55

5 jacent to the openings 13 whereby material passing between partitions of the adjacent edges of the openings, will be directed through the openings 13, while a portion of the material from which the sample is taken, passes between partitions of the adjacent openings, and will be directed through openings formed in the upper end 10 of the uppermost baffle plate 15 that extends into the hopper 12, from where the material moves over the riffler table 7, to contact with the riffler plates 10 and be directed through the openings 8, as the material flows to the lower end of the riffler table 7. Baffle plates indicated at 15 are arranged within the body portion 5, directly under the riffler table 7, and act to direct the material towards the bottom of the body portion, where the material passes through the discharge opening 16. The portion of the uppermost baffle plate 15 that extends into the hopper 12, is formed with openings through which the material under treatment passes to the riffler table.

25 A baffle member indicated by the reference character 17 is also arranged within the body portion, and is provided with an upper inclined wall 18, over which the material passes, which enters the body portion through the lowermost openings 8 of the riffler table 7.

30 Extending inwardly from the side walls of the body portion 5, are angle bars 19 that provide a support for the table 7, which is hingedly connected to the baffle plate 15 that extends into the hopper 12, as clearly shown by Figure 4 of the drawings. Nuts 20 are secured to the table 7, near the lower front edge thereof, and at points directly over the angle bars 19, the table 7 being formed with openings registering with the threaded openings of the nuts 20. Bolts 21 extend through the nuts 20 and have their inner ends resting on the angle bars 19, so that when the bolts 21 are rotated, the table 7, together with the riffler plates 10 supported thereon, will be adjusted vertically to any desired pitch depending on the flow of the material to be sampled, and 45 may be moved to a position as indicated in dotted lines in Figure 4 of the drawings. While the dotted line position shown by Figure 4 of the drawings, indicates the limit of the adjustment of the table 7, it is to be understood that the table 50 7 may be adjusted to various points between the dotted line position and full line position as shown by Figure 4 of the drawings, to adapt the device for use in treating various types of material. The body portion is supported on the beams 55 22 by means of the plates 23, that rest on the beams 22, as shown by Figure 1 of the drawings. Plates 23 are spaced apart, and form the upper and lower surfaces or walls of the endless conveyor housing, the spaces between the 60 plates 23 being closed by the side plates 24.

65 The reference character 25 designates the upper section of the endless conveyor housing, and rests on the upper plate 23 of the lower section of the endless conveyor housing, throughout a portion of the length of the conveyor 25. One end of the conveyor housing 25 extends upwardly as shown by Figure 1 of the drawings, where it is supported by the uprights 26 that also form a part of the vertical section of the conveyor housing.

70 The endless conveyor as indicated by the reference character 27, and includes spaced vertical strips 28 that slide over the lower surface of the conveyor housing, dragging material through the conveyor housing. The endless conveyor 27 op-

erates over the roller 29 at one end of the conveyor housing, from where it passes over the roller 30 disposed adjacent to the upper end of the vertical section of the conveyor housing, from where the endless conveyor operates over the 5 roller 31 mounted at one end of the lower section of the conveyor housing.

As shown, the conveyor housing extends through the body portion 5, at a point adjacent to the lower front edge of the riffler table 7, to receive material from the table 7.

Formed in the bottom of the lower section of the endless conveyor housing, is an opening 32 so that surplus material may pass from the conveyor housing and be directed to the body portion 5. One edge of the opening is inclined as at 33, providing an opening wide at one end, and narrow at the opposite end, with the result that material forming the sample and which is carried over the opening, will fall through the opening and be discharged into the body portion 5, from where the material will pass from the body portion through the opening 16. In this way, it will be seen that after the sample has been removed, the remaining portion of the sample will be returned to the body portion. As material is fed into the upper section of the conveyor housing, the material will be carried upwardly to the upper end of the conveyor housing, where it will be deposited in the chute 34 that in turn directs the material into the grinding machine 35 from where the material passes into the riffler 36 embodying the spaced riffler plates 37 that are disposed at opposite sides of the openings 38, the plates 37 being shown as converging towards the lower end of the riffler 36. These riffler plates 37 direct the material laterally and cause the material to be directed to the openings 38 of the riffler 36. After the material passes through the riffler 36, a portion of the material is deposited in the sample box 39 positioned at the discharge end of the riffler 36, as shown by Figure 1 of the drawings.

It will of course be understood that the material from which the sample is to be taken, is directed to the hopper 12 directly from the bins, in which the material is contained, and that by directing the material to the hopper 12, a sample may be readily and easily taken by separating a quantity of the material from the free flowing mass, to the end that a true sample may be obtained.

It might be further stated that the endless conveyor housing is closed throughout the length of the housing disposed within the body portion 5, by means of the hinged closure 43 that extends along the lower front edge of the body portion, the closure 43 moving upwardly with the riffler table 7, when an adjustment of the table 7 is necessary.

This closure also affords means whereby access may be had to the interior of the conveyor housing, should it become necessary to examine the conveyor or repair the same.

I claim:

1. A device for taking samples from free flowing material, comprising a body portion, an inclined riffler table forming a part of the body portion, transversely spaced partitions extending longitudinally of the table, said table having openings staggered with respect to each other and arranged on opposite sides of the partitions, rows of riffler plates arranged adjacent to the openings, guarding the front and side edges of the openings, the rear edges of the openings being open

- to the line of flow of material passing over the table, said riffler plates of adjacent rows being arranged in staggered relation with respect to each other, providing passageways between the 5 rows of riffler plates, and said riffler plates adapted to divide the material directing a portion of the material through the openings and a portion of the material to the passageways between the rows of riffler plates, and means at the lower end 10 of the table for carrying off the material discharged at the lower end of the table.
2. A device for taking samples from free flowing material, comprising a body portion, an inclined riffler table forming a part of the body portion, transversely spaced partitions extending longitudinally of the table, said table having openings staggered with respect to each other and arranged on opposite sides of the partitions, rows of riffler plates arranged adjacent to the 15 openings, guarding the front and side edges of the openings, the rear edges of the openings being open to a line of flow of material passing over the table, said riffler plates being secured to the riffler table throughout portions of their lengths, 20 and the remaining portions of the riffler plates being free to swing laterally for adjusting the riffler plates with respect to each other and providing irregular passageways between adjacent rows of riffler plates, and means for receiving the 25 material passing over the table.
3. A device for taking samples of free flowing materials, comprising a body portion, an inclined riffler table forming a part of the body portion, spaced partitions arranged on the table, said

table having openings disposed adjacent to the partitions, riffler plates positioned adjacent to the openings and closing the side and front end walls of said openings, the riffler plates being staggered with respect to each other and providing passageways between the free ends of the riffler plates through which material passes to the lower end of the table, a conveyor housing at the lower end of the table, an endless conveyor operating within the housing and onto which material passes from 10 the table, a plate dividing the upper and lower flights of the conveyor, and said conveyor housing having an opening through which material may pass from the housing.

4. A device for taking samples of free flowing 15 materials, comprising a body portion, an inclined riffler table forming a part of the body portion, spaced partitions arranged on the table, said table having openings disposed in staggered relation with respect to each other and located at 20 opposite sides of said partitions, riffler plates positioned adjacent to the openings and closing the side and front walls of the openings, said riffler plates having offset portions for directing material towards the passageways between the riffler 25 plates, the free ends of the riffler plates being adjustable laterally within the line of flow of material passing through the passageways, separating portions of the material and directing the material into the openings, and means for carrying off the material deposited at the lower end of the table.

JOSEPH L. SHULAR.
